US0D1037664S

(12) **United States Design Patent** (10) Patent No.: **US D1,037,664 S**
(45) Date of Patent: ** Aug. 6, 2024

(54) **STACKABLE STORAGE CRATE**

(71) Applicant: **CREATIVE PLASTIC CONCEPTS, LLC**, Sycamore, OH (US)

(72) Inventors: **Jacob H. Whitta**, Bluffton, OH (US); **Ben Sayalith**, Findlay, OH (US); **Eric Hummel**, Findlay, OH (US); **Tony Vilay**, Findlay, OH (US)

(73) Assignee: **CREATIVE PLASTIC CONCEPTS, LLC**, Sycamore, OH (US)

(**) Term: **15 Years**

(21) Appl. No.: **29/814,795**

(22) Filed: **Nov. 9, 2021**

(51) LOC (14) Cl. **09-04**

(52) U.S. Cl.

USPC **D3/307**
